RADIAL ARM TOOL FOR SAWING, PLANING OR THE LIKE

Anton Parisson, Brentwood, and Roger Protas, Pittsburgh,
Pa., assignors, by mesne assignments, to American
Machine & Foundry Company, a corporation of New
Jersey

Application June 19, 1957, Serial No. 46,645

Term of patent 14 years

(Cl. D93—3)

FIG. I.

Des. 186,423

PAGE 2

FIG. 2.

FIG. 3.

Fig. 1 is an enlarged front perspective view of a radial arm tool for sawing, planing or the like, showing our new design;

Fig. 2 is a front perspective view showing one side thereof; and

Fig. 3 is a perspective view showing the other side thereof.

We claim:

The ornamental design for a radial arm tool for sawing, planing or the like, substantially as shown.
